(57) **CLAIM**

We claim an ornamental design for a coated cooked whole egg, as shown and described.

DESCRIPTION

FIG. 1 is a perspective view of a coated cooked whole egg showing the claimed design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The evenly-spaced broken lines in FIGS. 1-6 illustrate portions of the coated cooked whole egg that form no part of the claimed design. The dash-dot-dash broken lines in FIGS. 1-6 illustrate the boundary of the claimed design which forms no part thereof.

1 Claim, 4 Drawing Sheets
